UNITED STATES PATENT OFFICE.

CHARLES A. LEFEVRE, OF PONTIAC, MICHIGAN.

CAN-OPENER.

1,287,358.

Specification of Letters Patent. Patented Dec. 10, 1918.

Application filed April 13, 1918. Serial No. 228,317.

To all whom it may concern:

Be it known that I, CHARLES A. LEFEVRE, a citizen of the United States, residing at Pontiac, county of Oakland, State of Michigan, have invented a certain new and useful Improvement in Can-Openers, and declare the following to be a full, clear, and exact description of the same, such as will enable others skilled in the art to which it pertains to make and use the same, reference being had to the accompanying drawings, which form a part of this specification.

My invention relates to can openers and a special object of my improvements is to provide for loosening the kind of covers that are pressed into the openings of cans and retained therein by friction, the cover at its edge overlapping the top of the can.

I secure this object in the device illustrated in the accompanying drawing in which:

Figure 1 is a perspective view of the upper part of a can with the cover and apparatus embodying my invention adjusted thereto.

Fig. 2 is a detail sectional view of the same.

Fig. 3 is a detail view of a part of the jointed rotating arm.

Fig. 4 is a sectional elevation showing the adjacent ends of cans where one is packed upon the other.

a is the cylindrical part of the can which has an inturned annular part or top *a*³. The rest of the top of the can is open and there is preferably a down-turned flange *a*² (Fig. 2) around the opening. *b* is a cover which is concave upward and convex downward as shown, the concave part being adapted to fit closely against the inner edges of the annular inturned portion, or top, *a*³ of the can. *b*² is an outwardly extending flange on the cover *b* which when the cover is in place rests against the upper surface of the annular portion *a*³ of the can.

At the center of the cover I secure a pivot piece *c* which may be in the nature of a headed rivet. Upon the pivot *c* I secure a flat arm *d* which may rotate on said pivot. *d*² is a second arm forming an extension of the arm *d* and pivoted thereto, so as to turn in a vertical plane, by means of a link *d*³ extending through eyes on adjacent ends of the arms *d* and *d*². The outer end of the arm

*d*² is bent back upon itself in a portion 55 marked *d*⁴ and is bent so that its inner end is at some distance from the main portion of the arm *d*². The edge at the inner end of the part *d*⁴ is chamfered and is shaped in the arc of a circle corresponding to the 60 periphery of the cover *b*, as shown in Fig. 3.

In the normal position of the arms *d* and *d*² the latter is turned backward upon the former, as shown by dotted lines in Fig. 2 and in full lines in Fig. 4, so that the whole 65 of both of said arms lies in the depression of the cover so that a second can may be placed upon the top of this can and lie smoothly thereon.

To loosen the cover the arm *d*² is turned 70 outward, as shown in Figs. 1 and 2, the edge *d*⁵ is forced under the flange *b*² and then the arms *d* and *d*² are rotated around the pivot *c* thus raising the flange from the annular portion *a*³ of the top of the can and 75 loosening the cover so that it can be readily removed.

While I prefer to bend the arm *d*² upon itself as shown and described of course the inwardly extending opening edge could be 80 otherwise provided.

What I claim is:

1. In combination with a can having a cover, said cover being provided with a circular outwardly extending flange in a plane 85 approximately parallel to the adjacent surface of the can, an arm formed of two parts, the inner part being pivoted to said cover at the center of the circle in which said flange lies so as to turn in a plane parallel 90 to that of said flange, said outer part being provided with an inwardly extending separating edge adapted to be inserted under said flange, the outer part of said arm being movable relative to the inner part. 95

2. In combination with a can having a cover, said cover being provided with a circular flange in a plane approximately parallel to the adjacent surface of the can, an arm formed of two parts, the inner part being 100 pivoted to said cover at the center of the circle in which said flange lies so as to turn in a plane parallel to that of said flange, the outer part being pivoted to the inner part so as to turn in a vertical plane at an angle 105 to the first named plane.

3. In combination with a can having a cover concaved outwardly, said cover being

provided with a circular flange in a plane approximately parallel to that of said cover, an arm formed of two parts, the inner part being pivoted to said cover at the center of 5 the circle in which said flange lies, said outer part being provided with an inwardly extending separating edge adapted to be in-

serted under said flange, the outer part of said arm being adapted to fold within the concavity of said cover for the purpose de- 10 scribed.

In testimony whereof I sign this specification.

CHARLES A. LEFEVRE.
